UNITED STATES PATENT OFFICE.

ANTONI KRUSZEWSKI, OF CLEVELAND, OHIO.

COMBINATION GARMENT-HANGER.

1,111,472.

Specification of Letters Patent. Patented Sept. 22, 1914.

Application filed January 31, 1914. Serial No. 815,752.

To all whom it may concern:

Be it known that I, ANTONI KRUSZEWSKI, a subject of the Emperor of Russia, residing at Cleveland, in the county of Cuyahoga and 5 State of Ohio, have invented certain new and useful Improvements in Combination Garment-Hangers, of which the following is a specification.

This invention relates to garment hangers, 10 and especially to a combination hanger for supporting two garments such as a coat and trousers.

The object of the invention is to provide a simple and improved device which can be 15 cheaply produced and which will be serviceable for the purpose indicated.

The structure comprises a coat supporter somewhat similar to those now in general use, modified to afford means for the attachment 20 of a clamping device by means of which trousers may be suspended from the same hanger.

The invention is illustrated in the accompanying drawings in which:—

25 is a perspective view showing the clamp for

Figure 1 is a side view showing the clamp for the trousers in open position. Fig. 3 is a side view of the coat hanger part, with the trousers clamp removed. Fig. 4 is a perspective view of the leaves of the trousers clamp illustrating the device for holding the same closed.

Referring specifically to the drawings, 6 indicates a wire coat hanger of ordinary construction with the addition, however, of a depending loop or part consisting of the vertical bars or rods 12 and 8^a and the connecting bar 11, as seen in Fig. 3. This is made of one piece of wire, coiled and bent as 35 shown in Fig. 3, the modified or depending part, as above referred to, serving for the support or attachment of the trousers hanger or clamp. This trousers hanger or clamp consists of three leaves, A, B and C, 40 preferably made of sheet metal of proper stiffness, and the leaves A and C are hinged

to the standing part 12 as indicated at 10. The middle leaf B is fixed at its opposite ends to the respective wires 12 and 8^a and is also bent at its lower edge around the cross 50 rod 11, whereby the plate or leaf B is held in a stiff and fixed position. The leaves A and C, located on opposite sides of the plate B, may be swung on their hinges toward and from the latter, and when closed they are 55 fastened by means of the hooks 9^a, carried by pins 9 arranged for rotation in a curl or bend formed at the ends of the leaves A and C, and the hooks 9^a are properly positioned to engage keepers 8^a formed by producing 60 opposite bends in the wire 8^a, one hook 9^a engaging the upper bend and the other hook engaging the lower bend.

In the use of the device, a coat may be 65 hung on the hanger in the usual manner. One or more pairs of trousers may be hung thereon by placing the same between the leaves A and C and the plate B, and then closing said leaves to clamp the ends of the trousers therebetween, the leaves being fastened by the hooks above described, said hooks being engaged by turning the rods 9 by means of the finger pieces at the lower 70 ends thereof.

What I claim as new is:

A garment hanger formed of a continuous wire, parts of which are bent to form two depending rods and a connecting cross rod, a plate fastened at its ends to the depending rods and attached along one edge to the 80 cross rod, a leaf hinged at one end to one of the depending rods and arranged to swing toward and from the plate, and a pin rotatably mounted on the free end of the leaf and having a catch engageable with the 85 other rod by turning said pin.

In testimony whereof, I do affix my signature in presence of two witnesses.

ANTONI KRUSZEWSKI.
